CONTROL AND OPERATING MECHANISM
FOR CENTRIFUGAL MACHINESOscar W. Johnson, Rochester, N. Y., assignor to
The American Laundry Machinery Company,
Norwood, Ohio, a corporation of Ohio

Application July 12, 1937, Serial No. 153,131

16 Claims. (Cl. 210—71)

This invention relates to control and operating mechanism for rotating bodies, such as extractors, including means for automatically unlatching and opening a safety cover for the extractor.

An object of the invention is to provide improved mechanism for controlling the operation of rotating bodies, such as extractors, by means of which energy is stored during the setting of a braking means which is operative to unlatch a safety cover for the rotating body when it comes to rest.

Another object of my invention is to provide improved mechanism for controlling the operation of a rotating body, such as an extractor provided with a safety cover, so that when a timer mechanism is set for a predetermined extraction period and the safety cover is moved to closed position, power means are initiated to operate the extractor, and at the end of the extraction period means become effective to disconnect the power means and set the brake, whereupon, when the rotating body comes to rest, energy stored during the setting of the brake releases the safety cover.

A further object of my invention is to provide an improved cover for rotating bodies, such as extractors, including means for maintaining the cover in latched position during the rotation of the body, and means for automatically unlatching the cover and moving it to open position when the rotating body comes to rest.

Further objects of the invention are in part obvious and in part will appear more in detail as the description proceeds.

In the drawings, which represent one suitable embodiment of the invention, Fig. 1 is a rear elevational view of an extractor with parts broken away to show the brake operating mechanism, the cover of the extractor being shown in open position and the controlling mechanism in the position it occupies when the extractor is idle.

Fig. 2 is a view similar to Fig. 1, showing the cover in closed position and the operating mechanism in the position it occupies when the extractor basket is rotating.

Fig. 3 is a plan view of the brake and associated control mechanism, showing parts in cross section.

Fig. 4 is a fragmentary detail view showing a portion of the brake and associated mechanism in the position it assumes just after the brake has been applied.

Fig. 5 is a detail elevation on the line 5—5 of Fig. 3.

Fig. 6 is a fragmentary detail view of a portion of the operating mechanism, showing its position at the end of the extracting cycle.

Fig. 7 is a side elevational view of the upper portion of the extractor, showing the position of the cover and associated mechanism when the cover is closed, a portion of the casing being broken away to show the latching arrangement.

Fig. 8 is a view similar to Fig. 7 showing the position of the cover and associated mechanism during the first stage of the opening movement.

Fig. 9 is a view similar to Fig. 7 showing the position of the cover and associated mechanism when the cover is open.

Fig. 10 is a diagrammatic view of the electric circuit for the control and operating mechanism.

20 While the invention is capable of application to any form of apparatus provided with a rotatable member brought to rest by a braking operation, it has more particular application to those machines in which the rotatable member is in the form of a container provided with a movable cover, such as a centrifugal extractor or other machine in which work is enclosed in a rotatable member. The drawings illustrate a centrifugal extractor of the general form shown in Letters

25 Patent No. 1,949,278, granted February 27, 1934, to George W. Johnson for Combined pressure and centrifugal extractors, to which reference may be had if desirable or necessary.

So far as description is necessary for the purpose of this application the extractor illustrated 30 comprises a stationary frame 1 including a plurality, three being shown, of hollow posts or pedestals 2, from the upper ends of which is suspended by rods, cables or the like (not shown),

40 a hollow nonrotatable curb or casing 3 provided with a hinged cover 4, and in which casing rotates the usual foraminous basket 5 driven in any suitable manner, such as by an electric motor 6 mounted on a lateral extension 7 from the curb.

45 As is usual the motor pulley is connected by a belt 8 to a wide pulley 9 on the basket shaft, a portion of pulley 9 being utilized for mechanical braking purposes, as will appear.

The cover 4 is mounted to turn upon a shaft 10 to the opposite ends of which are fixed links 11, which in turn are fixed to short shafts 12 journalled in bracket supports 13 on the curb. This construction not only permits the cover 4 to be swung back and forth, by hinging motion, 55 about the axis of shaft 10, but in addition, the

cover also has a horizontal motion by the swinging movement of the shaft 10 about the axis of the short shafts 12, the two motions being taken advantage of for control of the cover as will later appear.

The cover is biased toward open position by any suitable means, the drawings showing for the purpose an ordinary door closer 14, such as the standard Norton, Yates or other door closer which in the present instance operates in the reverse direction to open the cover and is therefore hereinafter called a door opener. The casing of the door opener includes an operating mechanism (not shown), always tending to turn the door opener shaft 15 in the counterclockwise direction, Fig. 7, said shaft having attached thereto an arm 16 connected by a link 17 to the cover 4.

The door opener shaft 15 also has fixed to turn therewith a short arm 18 connected by a link 19 to a rod 20 slidable vertically in guides 21 on the curb.

Shaft 10 also has fixed to turn therewith a member 22 (Fig. 7) of generally L-shaped form, having an upper arm 23 adapted to form a stop for the cover when it is in open position, a depending projection 24 adapted to engage a seat on the curb, and a second arm 25 connected by a link 26 to a member 27 slidable in a guide 28 on the curb and provided with a hook-shaped latching end 29 adapted for cooperation with a hook shaped latch 30 on a latch lever 31 pivoted on the curb. The cover also carries on its under surface, where it is inaccessible, and on its edge opposite to its hinge, a pivoted latch 32 normally biased outwardly or to latching position by a compression spring 33, said latch being adapted to engage beneath the curb wall for latching the cover down, as will more fully appear.

While any suitable devices may be used for stopping the rotating member or basket, I show for the purpose an ordinary band brake adapted to engage the braking portion of pulley 9, as before stated. The band brake includes the usual flexible metal braking member 34 provided with suitable brake lining material, one of the ends of said band being connected to a controlling device and the other end being associated with a device to be controlled now to be described. It will be assumed that the rotating member or basket, when operating rotates in the direction of the arrow A, Fig. 3. One end of the brake band is connected by a link 35 to one arm of a pivoted bellcrank lever 36, the other arm of which is slotted for connection to the pin of a clevis 37 on one end of a rod 38 passing through an opening in a stationary guide 39, beyond which it is provided with a collar 40 forming a seat for one end of a spring 41, the other end of which engages the guide 39. The free end of rod 38 is connected by a pivoted bellcrank lever 42 to a rod 43 sliding vertically in guides on the curb and provided with an abutment collar 44 having a beveled under portion 45 and adapted to cooperate with the hooked latching arm of a lever 46.

The opposite end of the brake band is connected to a rod 47 sliding in an opening in a fixed guide 48 beyond which is a compression spring 49 and a collar 50 fixed to the rod. The rod also carries a beveled abutment collar 51 adapted for by-pass cooperation with a spring pressed catch lever 52 on one arm of a bellcrank lever 53, the other arm of which is connected to a rod 54 slidable in a stationary guide 55

and provided with a fixed collar 56 and compression spring 57, beyond which said rod is connected by a pivoted bellcrank lever 58 to a rod 59 slidable through an opening in an arm of lever 31, below which it is provided with a fixed collar 60.

Control of and by the cover and brake mechanism in the particular form shown for illustration, involves the use of an electromagnet or solenoid 61, the core 62 of which is connected to a rod 63 slidable vertically in guides on the curb and provided with three fixed collars 64, 65, 66. Above collar 64 and below a stationary guide on the curb is a compression spring 61. Collar 65 cooperates with a compression spring 68 below an arm of lever 31. Collar 66 cooperates with a compression spring 69 below an arm of lever 46.

The electric control system is diagrammatically illustrated in Fig. 10. The motor is connected through a switch 70 to the lead wires L₁, L₂ and L₃. In a circuit 71 with two of said leads are included the coil of the solenoid 61 and also timing mechanism conventionally illustrated at 72. This timing mechanism may be of any suitable form, including a switch 73 in the circuit 71 adapted to be closed by operation of a manually operated setting device 74, which may be turned to set the timer for any desired period as well as to close switch 73 and energize the timer motor 75, which through mechanical connections 76 restores the setting mechanism to original position after the period for which the timer is set and automatically opens switch 73.

The control also includes a switch 77 in a parallel circuit 78 through a coil 79 adapted to operate the switch 70. Switch 77 may be of any suitable form, but it is biased to move in the switch closing direction, and is shown as provided with a pivoted angle shaped operating arm 77a provided with rolls 77b and 77c, and which arm controls switch operation, as will appear.

The operation is as follows:

Let us assume that the extractor is idle, with the cover open and with the basket filled with a load ready to be extracted. The cover rests against the stop arm 23, as shown in Fig. 9, and is held in that position by the biasing tendency of the door opener 14. The motor circuit is open at switch 70. The brake is released. Coil 61 is deenergized. Member 27 is in its lowermost position, as shown in Fig. 1, but the latch lever 31 is not in engagement therewith. Rod 43 is in its lowermost position as also shown in Fig. 1, but the latch lever 46 is not in engagement with the abutment collar 44. Spring 41 is compressed by the effect of collar 40. The braking parts, including band 34 have been moved in the counterclockwise direction (Fig. 3) around the basket shaft so far as they will go under the influence of the compression spring 49, latching parts 51, 52 being in the position shown in Fig. 3.

To start the machine the operator first sets the timer 72 by moving the manually adjustable setting part 74 along the scale to a position determining the period of extraction. This closes switch 73, thereby completing circuit 71 and energizing coil 61, the effect of which is to elevate the rod 63. Coil 61 remains energized and the rod 63 is held in its upper position until the extracting operation is completed, as will later appear.

There are several effects of the upward motion

of rod 63. First, spring 67 is compressed, storing power for later downward movement of said rod. Second, latch lever 31 is moved clockwise in Fig. 1 so that the hooks 30, 29 are engaged and member 27 is latched down, thereby holding member 23 in the position shown in Figs. 7 and 9, with the links 11 depending directly beneath the axis of the shaft 12. Third, lever 46 is moved into latching engagement with the abutment collar 44, preventing expansion of spring 41 such as might produce brake application, and thereby holding the brake released. Collar 60 lies just beneath an arm of lever 31 but the spring 57 is fully expanded.

The next operation is to manually close the cover, the operator pulling it down with simple swinging movement about the axis of shaft 10 until the biased latch 32 engages beneath the curb rim. This motion, of course, further energizes the door opener 14, storing power for later cover opening movement. Also, the link 19 is pulled up, elevating rod 20, which moves past roll 11c from the position shown in Fig. 1 to that shown in Fig. 2, permitting switch 71 to close, thereby energizing coil 79 which in turn closes switch 70 to the electric motor, and the rotatable member or basket begins to turn. Switch 71 does not close until the rod 20 passes roll 11c at which time the cover is in closed position.

The extracting operation proceeds, with the parts in the positions just described, until ultimately, after the expiration of the selected period, the timer 72 automatically opens switch 73, thereby deenergizing coil 61. The results are as follows:

Rod 63 suddenly moves downward under the influence of compression spring 67. Latch lever 31 remains in its then position. Latch lever 46 is tilted to unlatched position, out of latching relation with abutment 44. Thereupon brake actuating spring 41 expands, and through lever 36 applies tension to the brake and causes brake application. At the same time, the upper end of rod 43 engages roll 11b and opens switch 71, thereby deenergizing coil 79 so that the motor switch 70, which is biased toward open position, opens, cutting off current to the motor.

Application of the brake, by the effect of spring 41 not only applies the brake but moves the brake band clockwise in Fig. 3 around the axis of rotation of the basket to such extent as is permitted by the necessity for compression of spring 49, the clockwise motion of the brake band being amplified by the pull or drag of the pulley 9 upon the brake band. This motion is sufficient to allow the abutment collar 51 to move past the latch lever 52, from the position shown in Fig. 3 to that shown in Fig. 4. Now there is power stored in spring 49 tending to return the brake parts to their original position. The braking operation proceeds with application of braking friction to the pulley 9 until finally the rotating member or basket comes to rest. Thereupon the tendency of the rotating pulley 9 to move the brake band clockwise ceases, and the brake band naturally reacts against that tendency, in addition to which the spring 49 has an opportunity to expand and more positively turn the brake band in the counterclockwise direction, Fig. 3. During this motion abutment 51 engages the trip lever 52 and turns the bellcrank lever 53, pulling on rod 54, compressing spring 57 and also elevating rod 59, Fig. 1, the collar 60 of which raises the arm of latch lever

31 and turns it to unlatched position, releasing the member 27.

The cover is now latched only by the latch 32, which prevents its front edge from rising. Nevertheless it is under the biasing influence of the door opener 14 through arm 16 and link 17, and the effect of said door opener is to horizontally move the door from the position shown in Fig. 7 to that shown in Fig. 8, by producing swinging motion of the links 11. Finally, when the latch 32 moves beyond the edge of the curb the cover is entirely released and the door opener moves it to open position, shown in Fig. 6. Opening movement of the door causes downward motion of rod 19, which moves to the position shown in Fig. 1, passing down alongside of the switch 71 and engaging the upper end of rod 43, depressing said rod and moving the brake band fully to released position, at the same time compressing spring 41. This brings all of the parts back to their original positions at the beginning of the cycle, and the operations may then be repeated.

Of course, operation of the brake band by expansion of spring 49 moves the abutment 51 sufficiently and said abutment swings bellcrank lever 53 far enough so that abutment 51 passes the latch lever 52, finally reaching the position shown in Fig. 3. Also, as the door opens it engages the upper stop arm of member 23, restoring that member and links 11 to their original position as shown in Fig. 9.

What I claim is:

1. An apparatus of the class described, comprising a rotatable member, a cover for said member, means for starting rotation of said member and for simultaneously locking said cover in closed position so that it remains locked during the rotation of said member, means for applying a braking action to said rotatable member, and power means energized by the rotation of said member during brake application and operatively connected to the cover locking means for positively releasing the same when the rotatable member comes to rest.

2. An apparatus of the class described, comprising a rotatable member, a cover for said member, means for starting rotation of said member and for simultaneously locking said cover in closed position so that it remains locked during the rotation of said member, power operated means for rotating said member, means for applying a braking action to said rotatable member and for disconnecting the power operated means, means actuated by the rotation of said member during brake application and operatively connected to the cover locking means for positively releasing the same when the rotatable member comes to rest, and automatic means for opening said cover when the locking means is released.

3. An apparatus of the class described, comprising a rotatable member, braking means for said rotatable member, a cover for said member movable to open and closed position, a timer mechanism capable of being set to remain in operative position for a predetermined time, means responsive to the setting of the timer mechanism for locking said cover when it is moved to closed position, and means responsive to the timer mechanism at the termination of the period for which it is set for actuating said braking means, and means for releasing said locking means after the rotating member has come to rest.

4. An apparatus of the class described comprising a rotatable member, a cover for said member movable to open and closed position, an electric circuit including a timer mechanism capable of being set to operative position to close said circuit, means responsive to the closing of said circuit for locking said cover when it is moved to closed position, said timer mechanism being provided with means for opening said circuit after a predetermined period of time, and means responsive to the opening of said circuit for releasing the cover locking means.

5. An apparatus of the class described comprising a rotatable member, a cover for said member movable to open and closed position, a timer mechanism capable of being set to remain in operative position for a predetermined period of time, means responsive to the setting of the timer mechanism for locking the cover when it is moved to closed position, power operated means for rotating said member, braking means for said member, means responsive to the closing of said cover for initiating the power operated means, and means for actuating said braking means after the predetermined period for which the timer mechanism is set, and thereafter releasing said locking means after the rotating member has come to rest.

6. An apparatus of the class described comprising a rotatable member, a cover for said member movable to open and closed position, a timer mechanism capable of being set to remain in operative position for a predetermined period of time, means responsive to the setting of the timer mechanism for locking said cover when it is moved to closed position, power operated means for rotating said member, means responsive to the closing of said cover for initiating the power operated means, braking means for the movable member, means responsive at the termination of the period for which the timer mechanism is set for applying the brake to the movable member, and means actuated by the rotation of said member during brake application for releasing the cover locking means when the rotatable member comes to rest.

7. An apparatus of the class described comprising a rotatable member, a cover for said member movable to open and closed position, a timer mechanism capable of being set to remain in operative position for a predetermined period of time, means responsive to the setting of the timer mechanism for locking said cover when it is moved to closed position, power operated means for rotating said member, means responsive to the closing of said cover for initiating the power operated means, braking means for the movable member, means responsive at the termination of the period for which the timer mechanism is set for applying the brake to the movable member and disconnecting the power operated means, means actuated by the rotation of said member during brake application for causing release of the cover locking means, and means for automatically opening said cover when the rotatable member comes to rest.

8. An apparatus of the class described comprising a rotatable basket, a cover for said basket, motor means for rotating said basket, braking means for said basket, an electrical circuit including a source of electrical energy, a timer mechanism provided with means for closing said circuit for a predetermined period of time, said timer mechanism being operative after a predetermined period of time to break said circuit,

means responsive to the closing of the circuit for maintaining the brake in released position when the cover is closed, means responsive to the closing of said cover for supplying electrical energy to said motor means, and means responsive to the breaking of said circuit after the predetermined interval for simultaneously disconnecting the supply of electrical energy to said motor means and applying said braking means.

10. An apparatus of the class described comprising a casing, a cover for said casing movable to open and closed position, a rotatable basket arranged in said casing, motor means for rotating said basket, an electric circuit, a timer mechanism adapted to be set to close said circuit and being operable to open said circuit after a predetermined period of time, braking means, means responsive to the closing of said circuit for maintaining the cover in closed position, means responsive to the closing of said cover for supplying electrical energy to the motor means, means responsive to the opening of the circuit after the predetermined period for simultaneously applying the braking means and disconnecting the supply of electrical energy to the motor means, and means actuated by the rotation of said member during brake application to release the cover locking means when the rotatable basket comes to rest.

15. 30. An apparatus of the class described, comprising a rotatable member having an opening, a cover for said opening mounted for swinging movement about a shaft, depending hinge link means supporting said shaft to permit substantially horizontal advance movement of said cover, means for locking said cover closed in an advanced position, cover opening means associated with said cover and normally tending both to retract and also to swing the same about said shaft to open position when said locking means is released, said locking means serving to hold said cover in its advance position against the action of said opening means when said member is rotating, means for applying a braking effect to said member, and means energized by the rotation of said member during brake application for engaging and positively releasing the cover locking means when the rotatable member comes to rest.

16. 35. 40. 45. 50. 55. 60. 65. 70. 75. 11. An apparatus of the class described, comprising a rotatable member having an opening, a cover for said opening, locking means for said cover, braking mechanism including a flexible member associated with said rotatable member, means for operating said mechanism to apply the flexible member to said rotatable member to produce a braking effect thereon, means whereby the application of said brake mechanism to said rotatable body is effective to store energy in said flexible member, control means associated with said braking mechanism, means actuated by the energy stored in said flexible member for operating said control means when the rotatable member comes to rest, and means responsive to the operation of said control means for releasing said locking means, retracting said cover, and swinging it to open position.

12. An apparatus of the class described, comprising a rotatable member having a door, locking means therefor, braking mechanism for said member including a flexible brake band, operating means connected to one end of said band for applying it to said rotatable member, and an energy storing device connected to the other end of said band and in which energy is stored

during brake application, control means for said braking mechanism, and means actuated by said stored energy for releasing said locking means when the rotatable member comes to rest.

13. Apparatus of the class described, comprising a rotatable member having an opening, a cover for said opening, locking means for said cover, braking mechanism including a flexible band associated with said rotatable member, operating means connected to one end of said band for applying said braking mechanism to said rotatable member, an energy storing device connected to the other end of said band and in which energy is stored during brake application, control means associated with said braking mechanism, means actuated by said stored energy for operating said control means when the rotatable member comes to rest, and means responsive to the operation of said control means for releasing said locking means.

14. Apparatus of the class described comprising a rotatable member, a cover for said member movable to open and closed position, locking means for the cover, a brake for said member, means for applying and releasing said brake, a timer mechanism for determining operative cycles, means operatively associated with said cover locking means and with said timer means to position said cover locking means in cover locking position upon setting of the timer, an electrical circuit, a solenoid in said electrical circuit, a switch in said electrical circuit operatively associated with said timer, said brake application means being operatively linked to said solenoid, whereby, on termination of a cycle by said timer, said solenoid actuates said brake application means so as to apply said brake.

15. Apparatus of the class described comprising a rotatable member, a cover for said member movable to open and closed position, locking means for the cover, a brake for said member, means for applying and releasing said brake,

a timer mechanism for determining operative cycles, means operatively associated with said cover locking means and with said timer to position said cover locking means in cover locking position upon setting of the timer, an electrical circuit, a solenoid in said electrical circuit, a switch in said electrical circuit operatively associated with said timer, said brake application means being operatively linked to said solenoid, 10 whereby, on termination of a cycle by said timer, said solenoid actuates said brake application means so as to apply said brake to said rotating member, and means operatively associated with said brake and said cover release means for delaying operation of said cover release means until after the rotatable member has come to rest.

16. An apparatus of the class described, comprising a rotatable member, power supply means 20 for rotating said member, a cover for said member movable to open and closed position, latch means for holding said cover in closed position, a brake for said rotatable member, means for applying said brake, means operatively attached to said brake and abutting said latch, and actuated by the rotation of said rotatable member during brake application for releasing said cover latch and permitting said cover to swing to open position, a timer mechanism capable of being set 25 to remain in operative position for a predetermined period of time, means operatively associated with said cover to prevent energization of said power operated means until said timer is set and said cover is closed, and means operatively 30 associated with said timer, said brake applying means, and with said power supply means, to simultaneously disconnect the power supply and permit application of the braking means when said timer reacts to the termination of said predetermined period.

OSCAR W. JOHNSON.
